(57) **CLAIM**

The ornamental design for combined dashboard mount and holder for mobile devices, as shown and described.

DESCRIPTION

FIG. 1 is a front isometric view of a combined dashboard mount and holder for mobile devices showing our new design;

FIG. 2 is a rear isometric view thereof;

FIG. 3 is a top view thereof;

FIG. 4 is a front view thereof;

FIG. 5 is a rear view thereof;

FIG. 6 is a left side view thereof;

FIG. 7 is a right side view thereof; and,

FIG. 8 is a bottom view thereof.

The broken lines in the drawings depict parts of the combined dashboard mount and holder for mobile devices that form no part of the claimed design.
